(57) **CLAIM**

The ornamental design for a stand for monitor, as shown and described.

DESCRIPTION

FIG. 1 is a front perspective view of a stand for monitor showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a rear perspective view thereof;

FIG. 9 is an enlarged view of the encircled portion 9 in FIG. 1;

FIG. 10 is an enlarged view of the encircled portion 10 in FIG. 3;

FIG. 11 is an enlarged view of the encircled portion 11 in FIG. 4;

FIG. 12 is an enlarged view of the encircled portion 12 in FIG. 8; and,

FIG. 13 is a front perspective view of the stand for monitor in which a monitor is provided in broken lines to illustrate an example environment.

The evenly dashed broken lines shown in FIGS. 1-9 illustrate portions of the stand for monitor that form no part of the claimed design. The broken lines illustrating the monitor in FIG. 13 are environment, while the remaining broken lines in FIG. 13 illustrate portions of the stand for monitor that form no part of the claimed design. The dot-dash broken
